Attorney.

UNITED STATES PATENT OFFICE.

EDWARD G. BUDD, OF PHILADELPHIA, PENNSYLVANIA, ASSIGNOR TO BUDD WHEEL COMPANY, OF PHILADELPHIA, PENNSYLVANIA, A CORPORATION OF PENNSYLVANIA.

HUB-CAP-LOCKING DEVICE.

Application filed September 4, 1919. Serial No. 321,574.

To all whom it may concern:

Be it known that I, EDWARD G. BUDD, residing at Philadelphia, county of Philadelphia, State of Pennsylvania, have invented 5 certain new and useful Improvements in Hub-Cap-Locking Devices, of which I declare the following to be a full, clear, and exact description.

This invention relates to improvements in 10 hub cap locking devices for demountable wheels.

One of the objects of my invention is to provide an improved locking device for the hub caps of demountable wheels which is 15 simple in construction, "fool-proof" in operation, locks the hub cap positively to the inner hub and is of such a nature as not to detract from the artistic appearance of the hub cap.

20 Another object of my invention is to provide a hub cap of simple construction having a locking device which can be manufactured in large quantities at a comparatively low cost.

25 Another object of my invention is to provide a hub cap locking device of such a nature that the hub cap may be screwed up by hand, but will be locked against rotation to unscrew the hub cap, except when the 30 hub cap wrench is properly applied.

Further objects, and objects relating to economies of production and operation and details of construction, will definitely appear from the detailed description to follow. 35 I accomplish the objects of my invention, in one instance, by the devices and means described in the following specification. My invention is clearly defined and pointed out in the appended claims. A structure, constituting a preferred embodiment of my invention, is illustrated in the accompanying drawing, forming a part of this specification, in which:

Figure I is a transverse, sectional view 45 through the hub of a demountable wheel embodying my invention.

Figure II is a transverse, sectional view through the hub cap taken on the line 2—2 of Figure I.

50 Figure III is a transverse, sectional view through the hub cap taken on the line 3—3 of Figure I.

Figure IV is a view of the outer end of

the hub and hub cap corresponding to Figure I, but showing the wrench applied and 55 the latch released from engagement, and

Figure V is a view corresponding to Figure II but showing the wrench applied to release the latch.

In the drawings, similar reference numerals refer to similar parts throughout the several views and the sectional views are taken looking in the direction of the little arrows applied to the section lines.

Considering the numbered parts of the 65 drawing, I have shown a demountable wheel comprising the inner hub 15 and the outer hub 18. The axle shaft 11 extends within the usual axle casing 10, upon the outside of the end of which the bearings 12 are mounted. A bearing retainer 13 encloses said bearings and has a radially extending flange to which the brake drum 14 is bolted by bolts which also extend through a radial flange on the inner end of the inner hub so 70 that the brake drum, the bearing retainer, and the inner hub are bolted together, with the bearing, and the bearing retainer housed within the inner end of the inner hub, as shown in Figure I of the drawing. The 80 outer end of the inner hub is cylindrical or cup-shaped in form and internally threaded, and a plurality of bevelled ratchet teeth 17 are formed on the inner surface of the cup-shaped outer end 16 of the inner hub, beyond 85 the internal threads, as shown in Figure I. An outer hub 18 is removably mounted on the inner hub 15 and provided with pressed out seats 19 and 20 for the ends of the spokes. Any suitable intermeshing means 90 are provided to prevent relative rotation of the outer and inner hubs. The outer end of the outer hub 18 is bevelled at 21. In Figure I of the drawing, I have shown a rear wheel, the inner hub being so formed so as 95 to be mounted on the rear axle. It is to be understood, of course, that my invention is equally applicable to a front wheel, but as my invention has nothing to do with the mounting of the inner hub, I have not illustrated a front wheel.

The hub cap 22 has a cylindrical body portion which is externally threaded and screws into the internally threaded part of the inner hub. The hub cap has a cylindrical head which is larger in diameter than the 105

body portion, and the inner face of said head has a bevelled surface engaging and co-operating with the bevelled end 21 of the outer hub. An opening is provided through the 5 side wall of the body portion 23 of the hub cap between the inner face of the head and the threaded portion of said body, and there is also provided an opening 24 through the side wall of the head in line with the previously 10 described opening through the side wall of the body. A latch 25 is mounted within the hub cap and has a bevelled tongue 27 which is slidably mounted in the opening through the side wall of the body portion 15 of the hub cap and engages the internal bevelled ratchet teeth 17 of the inner hub as clearly shown in Figure III. The latch 25 also has an actuating pin 26 which is slidably mounted in the opening 24. The tongue 27 and the actuating pin 26 extend laterally from the latch 25 at substantially right angles thereto. A guide pin 28 extends from the latch 25, in the opposite direction from the tongue 27; and is in line 20 with a similar guide pin 30 which extends laterally from the side wall of the hub cap at a point diametrically opposite. A compression spring 29 is compressed between the latch 25 and the side wall of the hub cap, 25 the ends of said spring being centered around the pins 28 and 30.

To rotate the hub cap, I use a wrench 31 having a shoulder 32 and a curved arm 34, from the end of which a pin 33 projects laterally. When it is desired to rotate the hub cap, the pin 33 is inserted in the opening 24, and the shoulder 32 engages the side of the head of the hub cap, thus giving the wrench a grip on the hub cap by means of which 30 it may be rotated. The insertion of the pin 33 in the opening 24 presses back the actuating pin 26 and the latch 25 against the pressure of spring 29, thus withdrawing the bevelled tongue 27 from engagement with the bevelled ratchet teeth 17, so that the hub cap may be rotated freely. As soon as the wrench is removed, the spring 29 presses back the latch so that the tongue 27 moves 35 into engagement with the ratchet teeth, the bevel of the tongue 27, and of the ratchet teeth 17, being such as to permit the rotation of the hub cap in a direction to screw up the hub cap, while preventing all rotation in the opposite direction. The end of 40 the actuating pin 26 is normally substantially flush with the surface of the hub cap, and, if for any reason the latch does not move out into engagement with the ratchet teeth, this will be indicated by the fact that 45 the end of the pin 26 is not out flush with the surface of the head of the hub cap.

I have heretofore described in some detail the operation of this locking device and further description is unnecessary. It is apparent 50 that it may be made of few parts, and

readily yields itself to embodiment in a hub cap of very simple construction, and that in the use of this type of locking device, the outer end or head of the hub cap may be cylindrical and of very substantial appearance, so that this construction does not detract from the artistic appearance of the hub cap. 70

I am aware that the particular embodiment of my invention, which I have shown and described here, is susceptible of considerable variation without departing from the spirit thereof, and, therefore, I desire to claim the same broadly, as well as specifically, as indicated by the appended claims. 80

Having thus described my invention, what I claim as new and desire to secure by Letters Patent, is:—

1. A device of the class described comprising the combination of an inner hub, an outer hub removably mounted thereon, a hub cap detachably mounted on one of said hubs and having an uninterrupted surface engaging the other to hold said hubs in engagement, said hub cap having a pair of transverse aligned openings through the side wall thereof, and a latch having a tongue slidably mounted in one of said openings and an actuating pin slidably mounted in the other opening. 95

2. A device of the class described comprising the combination of an inner hub, an outer hub removably mounted thereon, a hub cap detachably mounted on one of said hubs and having an uninterrupted surface engaging the other to hold said hubs in engagement, said hub cap having a pair of aligned openings in the side wall thereof on opposite sides of said surface, and a latch having a tongue slidably mounted in one of said openings and an actuating pin slidably mounted in the other opening. 100

3. A device of the class described comprising the combination of an inner hub, an outer hub removably mounted thereon, said inner hub having a plurality of internal ratchet teeth formed therein, a hub cap screwed on the inner hub and having an uninterrupted surface engaging the outer hub to hold said hubs in engagement, said hub cap having a pair of openings through the side wall thereof, a latch extending in a direction parallel to the axis of said hub cap and reciprocable radially thereof and having a bevelled tongue slidably mounted in one of said openings and engaging said ratchet teeth and an actuating pin slidably mounted in the other opening, and a spring compressed between said latch and the side wall of said hub cap. 115

4. A device of the class described comprising an inner hub, an outer hub removably mounted thereon, a hub cap screwed on said inner hub and having an enlarged head overhanging and with an uninterrupted sur- 120 125 130

face engaging the outer end of the outer hub cap, an actuating pin mounted in the hub, said enlarged head having a radial opening in said head, and a locking tongue mounted in the opening through said side wall. 10
5 in line with the first-mentioned opening, and a radially reciprocable latch having a body portion extending parallel to the axis of the

In testimony whereof, I affix my signature.

EDWARD G. BUDD.
